UNITED STATES PATENT OFFICE.

HERBERT S. JANDUS AND JOHN RICHARD MORGAN, OF DETROIT, MICHIGAN, AS
SIGNORS TO THE C. G. SPRING & BUMPER COMPANY, OF DETROIT, MICHIGAN, A
CORPORATION OF DELAWARE.

DESIGN FOR A CLAMP PLATE.

Application filed March 7, 1928. Serial No. 25,731. Term of patent 14 years.

To all whom it may concern:

Be it known that we, HERBERT S. JANDUS and JOHN RICHARD MORGAN, citizens of the United States, residing at Detroit, in the county of Wayne and State of Michigan, have invented a new, original, and ornamental Design for a Clamp Plate, of which the following is a specification, reference being had to the accompanying drawing, forming

ing part hereof, wherein Fig. 1 represents a front elevation and Fig. 2 represents a side elevation of a clamp plate exhibiting our new design.

We claim:

The ornamental design for a clamp plate, substantially as shown.

HERBERT S. JANDUS.
JOHN RICHARD MORGAN.
